Lancaster Thomas.

United States Patent Office.

LANCASTER THOMAS, OF PHILADELPHIA, PENNSYLVANIA.

Letters Patent No. 79,162, dated June 23, 1868.

IMPROVEMENT IN BOTTLE-MOULDS.

The Schedule referred to in these Letters Patent and making part of the same.

TO ALL WHOM IT MAY CONCERN:

Be it known that I, LANCASTER THOMAS, of the city of Philadelphia, county of Philadelphia, and State of Pennsylvania, have invented a new and useful Improvement in "Bottle-Moulds;" and I do hereby declare that the following is a full, clear, and exact description of the construction and operation of the same, reference being had to the accompanying drawings, making a part of this specification, in which—

Figure 1 is a perspective view of mould when closed.

Figure 2 is a side view of same when open.

Figure 3 is a section through A B.

The object of my invention is to save expence in the manufacture of stamped bottles, by making one mould answer the purpose for moulding any name or address on bottles, without going to the expense of getting up new moulds entire.

To enable others skilled in the art to make and use my invention, I will now proceed to describe its construction and operation.

I make my mould of any form desired, in the top, bottom, or sides of which I make one or more openings, as shown in fig. 2. Said openings can be made round, square, elliptical, or in any other form. In these openings are inserted a plug or die, D, the inner side of said die being made to conform to the mould. When the die is inserted in place, the edge projects slightly into the mould, as shown in fig. 3, for the purpose of allowing a free removal of the bottle. On the face of the die are stamped or cut letters or numbers, or any design whatever that is required on the side of the bottle. The die is connected with the mould by hinges, or otherwise, in such a manner that it may be removed, or opened and closed, at pleasure. It will be seen from this that any number of dies, of different designs, can be used without getting up entire new moulds.

Having thus described my invention, what I claim, and desire to secure by Letters Patent of the United States, is—

The application of a plug or die of any device to bottle-moulds, when the same is arranged in the manner and for the purpose above set forth and described.

LANCASTER THOMAS.
